UNITED STATES PATENT OFFICE.

JOHN MILTON JOHNSTON, OF CHICAGO, ILLINOIS.

CABINET FOR EXHIBITING EYE-TESTING DEVICES.

SPECIFICATION forming part of Letters Patent No. 730,023, dated June 2, 1903.

Application filed September 18, 1901. Serial No. 75,324. (No model.)

To all whom it may concern:

Be it known that I, JOHN MILTON JOHNSTON, a citizen of the United States, residing at Chicago, in the county of Cook and State of Illinois, have invented certain new and useful Improvements in Cabinets for Exhibiting Eye-Testing Devices, of which the following is a specification.

My invention relates to improvements in cabinets for exhibiting eye-testing devices; and the main object of my invention is the provision of a single-cased device containing mechanisms for performing the different tests employed by oculists and opticians, and thus dispense with a number of separate complicated devices, as is the present use.

To attain the desired objects, the invention consists of an eye-testing device embodying novel features of construction and combination of parts, substantially as disclosed herein.

In the drawings, Figure 1 is a front elevation of the device. Fig. 2 is a vertical central section thereof. Fig. 3 is a front elevation of the device with the front removed, and Fig. 4 is an enlarged detail view of one of the shafts carrying the astigmatic letters.

Referring by numeral to the drawings, the numeral 1 designates a casing, which may be rectangular in form; but I prefer to make it in the form of a clock. Formed in the upper front of the casing is the long rectangular opening 2, through which are adapted to be observed letters or numbers or other characters carried upon the transparent band 3, passed behind this opening by means of the rollers 4 and 4^a, which are journaled in the bearings 5 in the sides of the casing. A light 6 is employed when needed to cause the letters to be plainly seen and may be in the casing or in any convenient position outside. To revolve the rollers, I employ the cord 7, which is secured to the drum or spool 8, fastened upon the end of the roller 4^a. From this drum the cord passes downward around the pulley 9, to and around the spool or wheel 10, mounted upon supporting-bolt 11 of shaft 12, upon whose outer end 12^a is rigidly secured the dial 13. A portion of this shaft is cut away, as shown in Fig. 2, to provide a space for the mounting of the spool or wheel 10, upon whose outer face is fastened the band or strip 14, which is bent inward to

form the two indicators 14^a upon the outside of the dial. The cord 7 after circling the spool 10 passes out through the side of the casing and is provided with a button 15, which allows the same to be pulled upon to operate the transparent band and the dial's indicators. The roller 4, being provided with a spring-roller, such as a curtain-roller, allows the cord to be pulled into the casing automatically and also allows the stopping of the indicators and band at any desired place.

Below the roller 4^a and journaled in the bearings 16 on the inside of the casing is the roller 17, which carries a shade or curtain 18, upon which is printed the prism-test 19, consisting of two series of dots, letters, and numerals, said dots and numerals being printed in different colors. This curtain is adapted to be drawn forward and downward in front of the dial by means of the cords 20, which are connected to the roller 22. A grooved pulley-wheel 24 is employed to revolve the roller 22, and thus operate the curtain.

In the face of the casing, arranged in the form of corners of a square around the dial, are the four rectangular openings 25, through which are adapted to be observed the astigmatic letters 26, which are mounted upon the outer free ends of the disks 27, carried by the shafts 28. These shafts 28 are made substantially in two parts, the disks being upon the short outer ends and the inner ends 29 being the longer portions. The disk is provided with the groove or channel 30 for the reception of the operating-cord 31, a socket 32 and a set-screw 33 being carried by the outer end of the shaft 28, so as to connect the longer portion 29 securely to the lug or projection 34 thereof. To operate these shafts, I employ the cord 31, having at its respective ends the buttons 37. The cord 31 is passed around shafts 28, being then passed through the side and provided with a button. When this button is pulled upon, the shafts revolve simultaneously.

From this description, taken in connection with the drawings, the operation of my improved eye-testing device is readily understood and its numerous advantages over any of the devices now in use is readily appreciated.

It has been my intention to provide an eye-

testing-device cabinet which dispenses with the numerous and complicated instruments and devices used at present and produce one which embodies all the important mechanisms 5 for performing these tests, and by this construction and arrangement I produce a very simple and inexpensive device.

What I claim is—

An eye-testing device, comprising a base, 10 a rear wall, side walls and a front wall mounted upon said base, said rear wall and front wall being provided with four pairs of alined bearings, shafts mounted in said bearings, two upper pairs of bearings and two lower pairs 15 of bearings carried upon opposed sides of the side walls, a series of shafts mounted in said bearings, a continuous belt carried by the upper pair of shafts, a curtain carried by the lower pair of shafts and adapted to be moved 20 up and down by rotating said shafts, a shaft

12 mounted in the rear of the casing, a circular disk carried upon the front end of said shaft, mechanism to revolve simultaneously said shaft 12 and the upper pair of shafts carrying the belt, mechanism to revolve the four 25 first-mentioned shafts, and disks carried upon the outer ends of the four first-mentioned shafts; said front wall of the casing being provided at its top with a rectangular opening adjacent to the continuous belt, a lower 30 circular opening adjacent to the disk carried by shaft 12, and a series of rectangular openings adjacent to the disks carried by the first-mentioned shafts.

In testimony whereof I affix my signature 35 in presence of two witnesses.

JOHN MILTON JOHNSTON.
